DESIGN FOR A CASE FOR A CAMERA

Bruno Mayer, New York, N. Y.

Application June 1, 1946, Serial No. 130,313

Term of patent 14 years

(Cl. D61—1)

To all whom it may concern:

Be it known that I, Bruno Mayer, a citizen of the United States, residing in New York, in the county of New York and State of New York, have invented a new, original, and ornamental Design for a Case for a Camera, of which the following is a specification, reference being had to the accompanying drawing, forming part thereof, in which:

Fig. 1 is a front elevational view of a case for a camera embodying my new design;

Fig. 2 is an end view;
Fig. 3 is a rear elevational view;
Fig. 4 is an end view from the opposite end from that of Fig. 2; and
Fig. 5 is a top plan view of the case.

I claim:
The ornamental design for a case for a camera, substantially as shown.

BRUNO MAYER.
